UNITED STATES PATENT OFFICE.

EMIL F. NORELIUS, OF PEORIA, ILLINOIS, ASSIGNOR TO THE HOLT MANUFACTURING COMPANY, OF STOCKTON, CALIFORNIA, A CORPORATION OF CALIFORNIA.

GUN-MOUNT BRAKE.

Application filed August 27, 1919. Serial No. 320,238.

To all whom it may concern:

Be it known that I, EMIL F. NORELIUS, a citizen of the United States, residing at Peoria, in the county of Peoria and State 5 of Illinois, have invented a new and useful Improvement in Gun-Mount Brakes, of which the following is a specification.

This invention relates to tractor gun mounts, and more especially to a brake for 10 tractor truck mechanism whereby the force of recoil of a gun is counteracted.

A chain track type of tractor is used as a gun mount and has an internal expanding 15 brake fixed upon the driving sprocket wheels, said brakes being capable of being set so that when the gun recoils the driving sprocket wheels will be held or restrained against turning, with the result that the tractor will be held more or less in position 20 and the force of the recoil will be taken up by the usual recoil mechanism of the gun.

Brake mechanism heretofore used in connection with tractors of this type has been applied to the transmission mechanism, but 25 to attempt to use such brakes for the present purpose would impose severe and disastrous strains upon the comparatively delicate driving mechanism. In the present device I apply the brake mechanism directly to the 30 driving sprocket wheels so that danger of breakage is not present and the action of the brake is more direct and effective.

Referring to the accompanying drawings:

Fig. 1 shows a side elevation of a tractor 35 gun mount embodying my invention.

Fig. 2 shows a side elevation of the brake band and hand wheel for manipulating the brakes.

Fig. 3 shows a sectional view of the driving sprocket wheel and connected brake mechanism taken on the line 3—3 of Fig. 2.

Fig. 4 shows a detail sectional view of one of the pins for fastening the hand wheel in place.

Fig. 5 shows a circumferential sectional view of the brake mechanism taken on the line 5—5 of Fig. 6.

Fig. 6 shows a sectional view taken on the line 6—6 of Fig. 5.

Fig. 7 shows a sectional view in plan of a conventional type of driving mechanism

for the toothed sprocket wheels, to which sprocket wheels the brake mechanism is applied.

Fig. 8 shows a plan view, partly in section, 55 of a continuation of the driving and transmission mechanism of Fig. 7.

The tractor gun mount shown herein may comprise a main frame 10 on which a gun 11 is mounted, this frame carrying and supporting also an engine and other operating parts for driving the tractor. At each side of the main frame is a tractor truck mechanism comprising a truck frame 12 fitted with a series of flanged rollers 13 at its lower 60 edge and with an idler sprocket wheel 14 at its forward end. The main frame is carried directly upon and supported by these truck frames 12 in any one of several different well known ways, preferably so as to cushion the 65 main frame and to allow more or less rocking movement of the truck mechanisms independently of the main frame.

An endless chain track 15 passes around the idler wheel 14 and beneath the rollers 75 13 and is carried upon and driven by a toothed sprocket wheel 16, the latter being journaled directly upon the main frame. The means for driving the toothed sprocket wheel varies in different designs of tractors, 80 the one shown herein including a spur gear 17 supported upon an axle 18 and connected to the toothed sprocket wheel by means of a sleeve 19. A spur pinion 20 meshes with the gear 17 and is connected by means of a sleeve 85 or hub to a second spur gear 21, which, in turn, meshes with a second spur pinion 22. The last-named spur pinion is driven from a fore and aft extending propeller shaft 23 through the medium of bevel gears 24. 90 All of said gears and connected parts are journaled in a housing 25 carried upon the main frame.

Upon each of the toothed sprocket wheels 16 is formed a drum or band 26 on the exterior face thereof and within this band is arranged a spider 27 fixed upon a sleeve 28, which sleeve is mounted loosely on an extension 29 of the axle 18 of the driving wheel. The spider is held against turning 95 movement by means of a bar or link 30 connected thereto and to the adjacent truck 100

frame 12. A pair of brake segments 31 is carried upon the spider 27 and they are movable radially by means of oppositely extending screw shafts 32 fed by a sleeve 33, which 5 sleeve is turned by a spiral gear 34. A worm gear 35 is formed on a sleeve 36, which sleeve is journaled on the sleeve 28. For turning the sleeve 36 for the purpose of manipulating the screw feed device I provide a hand 10 wheel 37 at the exterior of the brake mechanism, said hand wheel being fastened to a flange on the sleeve 36 by means of bolts 38 working in slots 39 formed on the inner portion of the hand wheel. These bolts 38 15 are spring pressed to hold them in place and the slots 39 are provided near their centers with enlarged portions to permit the heads of the bolts to pass through when it is desired to remove the hand wheel.

20 In the operation of the device the gun is set in firing position and thereafter the brakes are set by means of the hand wheel 37. The force of the recoil of the gun is transmitted to the truck mechanism in a 25 direction to drive the tractor rearwardly as a whole, but to so move the tractor it is necessary that the toothed sprocket wheels turn, inasmuch as these sprocket wheels mesh with the chain track and the chain 30 track in a machine of this character will not allow of any slippage. However, since these toothed sprocket wheels are restrained against turning movement by the brake mechanism described, it will be seen that the 35 tractor will be held more or less in position and the force of the recoil will necessarily have to be taken up by the recoil mechanism of the gun.

It will be understood that the present 40 mechanism is more effective than ordinary wheel brakes used on round wheels, since such round wheels will slide or slip even when braked. The present brake mechanism may be set to take up as much or as little 45 of the recoil as desired. When the tractor is being moved from one position to another the hand wheels for setting the brakes may be taken off on account of the detachable connections described.

50 I wish it understood that various changes in the construction, combination and arrangement of parts may be resorted to without departing from the spirit of my invention as disclosed in the appended claims.

55 Having thus described my invention, what I claim and desire to secure by Letters Patent is:

1. In a tractor, a main frame, a chain track truck mechanism at each side of the 60 main frame, said truck mechanism including an endless chain track, a toothed sprocket wheel for driving the same and a load carrying truck within the track, a 65 brake mechanism arranged on said sprocket wheel to restrain the latter against turn-

ing movement by thrusts imparted to it by the main frame, said brake mechanism comprising a drum fixed upon the sprocket wheel, internally expanding shoes co-operating with the drum and means connected with 70 the load-carrying truck to hold the brake shoes against turning movement.

2. In a tractor, a main frame, a chain track truck mechanism at each side thereof, said truck mechanism including an endless 75 chain track, a toothed sprocket wheel for driving the same, and a load carrying truck within each track, a brake mechanism arranged on said sprocket wheel to restrain the latter against turning movement by 80 thrusts imparted to it by the main frame, said brake mechanism comprising a brake drum fixed upon the sprocket wheel, a spider carried within the drum and mounted 85 loosely upon the axle of the sprocket wheel, means between the load carrying truck and the spider to prevent turning movement of the latter and internally expanding brake shoes carried by the spider for co-operation 90 with the drum.

3. In a tractor, a main frame, a chain track truck mechanism at each side, each truck mechanism including an endless chain track, a driving sprocket wheel therefor and a load carrying truck within the track, 95 a drum fixed upon the sprocket wheel, a spider loosely mounted on the axle of the sprocket wheel, internally expanding brake shoes carried upon the spider, means to prevent turning of the spider on the axle, screw shafts to move the brake shoes radially, a screw-threaded sleeve to operate said shafts and worm gearing to operate said screw-threaded sleeve.

4. In a tractor, a main frame, a chain 105 track truck mechanism at each side thereof, each including an endless track, a driving sprocket wheel and a load carrying truck within the track, a drum fixed upon the sprocket wheel, a spider loosely mounted 110 on the axle of the sprocket wheel, internally expanding brake shoes carried by the spider, means to prevent turning movement of the spider on the axle, screw-threaded connections to operate the brake shoes radially, 115 a worm gear loosely mounted on the axle for actuating said screw-threaded connections and a hand wheel for driving said worm gear.

5. In a gun mount, a carrying and supporting frame for the gun, a chain track truck mechanism on which this frame is arranged, said truck mechanism including an endless chain track and a toothed sprocket wheel 120 co-operating with said track, a brake mechanism, arranged on said toothed sprocket wheel to restrain the latter against turning movement to prevent movement of the truck mechanism under the shock of recoil of the gun, said brake mechanism comprising 125 130

ing a brake drum fixed upon the toothed sprocket wheel, a spider carried within the drum and held against turning movement, a pair of brake shoes carried by the spider, 5 and a hand wheel at the outside of the sprocket wheel operatively connected with the brake shoes for setting the latter.

In testimony whereof I have hereunto set my hand in the presence of two subscribing witnesses.

EMIL F. NORELIUS.
